(57) **CLAIM**

The ornamental design for a chug lid, as shown and described.

DESCRIPTION

FIG. 1 is a perspective view of a first embodiment of a chug lid in a closed state, in use condition, showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a perspective view of a second embodiment of a chug lid in an open state, in use condition;

FIG. 9 is a front view thereof;

FIG. 10 is a back view thereof;

FIG. 11 is a left view thereof;

FIG. 12 is a right view thereof;

FIG. 13 is a top view thereof;

FIG. 14 is a bottom view thereof;

FIG. 15 is a perspective view of a third embodiment of a chug lid in a closed state, in use condition;

FIG. 16 is a front view thereof;

FIG. 17 is a back view thereof;

FIG. 18 is a left view thereof;

FIG. 19 is a right view thereof;

FIG. 20 is a top view thereof;

FIG. 21 is a bottom view thereof;

FIG. 22 is a perspective view of fourth embodiment of a chug lid in an open state, in use condition;

FIG. 23 is a front view thereof;

FIG. 24 is a back view thereof;

FIG. 25 is a left view thereof;

FIG. 26 is a right view thereof;

FIG. 27 is a top view thereof; and,

FIG. 28 is a bottom view thereof.

The broken lines in the drawing views represent unclaimed portions of a chug lid, which are included for the purpose of illustrating unclaimed environment only, and forms no part of the claimed design.

1 Claim, 26 Drawing Sheets
